COLLAPSIBLE POURING SPOUT

Cornelius W. Meyers, Portland, Oreg.

Application August 13, 1948, Serial No. 44,131

3 Claims. (Cl. 222—501)

1

My invention pertains to pouring spouts, and relates particularly to a collapsible pouring spout which may be readily inserted in the bung hole of a barrel and may be pushed into said barrel when not in use.

It is a principal object of my invention to provide a collapsible pouring spout made of rubber or other flexible material and which may be removably inserted in the bung hole of a barrel for dispensing liquids therefrom.

Another object is the provision of a pouring spout which may be attached to the bung hole cap, whereby said pouring spout may be stored within the barrel when not in use and may be inserted in said bung hole by pulling outwardly on said cap.

Other objects and advantages of my invention will appear from the following detailed description taken in connection with the accompanying drawing in which:

Fig. 1 is a plan view, partially in section, illustrating the structural features of a pouring spout embodying my invention;

Fig. 2 is an elevation taken along the line 2—2 of Fig. 1, parts being broken away to show structural details of the pouring spout outlet and the plug valve;

Fig. 3 is a sectional view taken along the line 4—4 of Fig. 1;

Fig. 4 is a sectional view similar to Fig. 3 illustrating the manner in which the pouring spout is folded or collapsed preparatory to insertion in the bung hole of a barrel; and

Fig. 5 is a section taken along the line 5—5 of Fig. 1, showing the manner in which the valve stem is secured to the bung hole cap.

The pouring spout embodying my invention comprises a flexible cylindrical body 1 molded of rubber or similar resilient material. A partition 2 is formed transversely in said cylinder at a distance from the closed end 3 thereof, and a portion of the body 1 between the partition and the closed end is cut away to form a discharge spout 4 through which the liquid contained in the barrel may be dispensed.

An aperture 5 is formed in the partition 2 in the shape of a truncated cone which tapers inwardly toward the discharge spout 4. A conical valve 6 of hard rubber or other substantially rigid material is constructed and arranged to be releasably seated in said aperture 5. One end of a valve rod 7 is molded into or otherwise securely attached to the valve and extends outwardly through a hole 8 formed in the closed end 3 of the body. To the terminal end of the valve

2

rod is secured a U-shaped fitting 9. A pin 10 extending transversely through said fitting engages a loop 11 which is secured to the bung hole cap 12. The cap is thus pivotally connected to the valve 6, and the latter may be pulled into and pushed away from the aperture 5 by manipulating the cap.

The intermediate portion 13 of the body 1 is of smaller diameter than the open end portion 14. These sections are joined by a smooth surfaced tapered portion 15 which affords easy insertion of the body into the bung hole 16 of the valve 11. The end portion 14 has an outward diameter slightly greater than the diameter of the bung hole in order to provide a snug compressive fit and a positive seal therebetween. A shoulder 18 extends circumferentially about the end portion 14 to form a stop and a sealing flange between the inner wall of the barrel and the body 1, thereby to prevent leakage of liquid from the barrel. The top portion 19 of said shoulder, i. e. the portion diametrically opposite the discharge spout 4, is preferably cut off to decrease the resistance of said shoulder to pressure applied when it is desired to collapse the body, as explained hereinafter. In addition, slots 20 are cut in said shoulder on opposite sides of the top portion 19 to reduce the elastic strength of the shoulder and permit easy distortion of the body during collapsing of the latter.

In installing the pouring spout in the barrel after the bung hole cap 12 has been attached to the valve rod 7, thumb pressure is applied upon the reduced top portion 19 of the shoulder 18 until the open end of the body 1 collapses to the shape illustrated in Fig. 4 of the drawing. The body is thus reduced in outside dimension sufficiently to permit insertion in the bung hole 16. When the body has been inserted in the bung hole the hand pressure is relaxed and the body springs outwardly from its collapsed condition to the arrangement shown in Fig. 3. Ordinarily the pouring spout will be pushed into the barrel and the cap 12 secured in place preparatory to shipping the barrel and its contents to the consumer. In this manner the barrel is equipped with a pouring spout which is readily available when the cap is removed.

When it is desired to remove liquid from the barrel, the latter is rested on end and the cap 12 is unthreaded from the bung hole 16. When the cap is pulled outwardly from the barrel the valve rod 7 is drawn outwardly through the hole 8 and the valve 6 moves into the aperture 5. By virtue of the conical shape of the valve the latter

is readily centered in the aperture. When the valve has been seated firmly in the aperture 5 further pull on the cap 12 causes the body 1 to be drawn outwardly through the bung hole. When the tapered portion 15 of the body engages the peripheral wall defining the bung hole additional pulling force is required in order to draw the enlarged portion 14 into the hole. By moving the body in a see-saw fashion or wiggling it simultaneously while pulling thereon, the former is drawn into and seated in the hole. The raised shoulder 18 abuts against the inner margin of the bung hole and prevents complete withdrawal and separation of the body from the barrel. The pouring spout embodying my invention is now ready for use, and the barrel may be arranged on its side upon a suitable support.

In drawing liquid from the barrel the cap 12 is pushed inwardly toward the barrel to unseat the valve 6 and provide passage of liquid through the aperture 5. The area of the aperture may be varied, to regulate the volume of discharge from the barrel, by moving the valve selected distances away from the aperture. When the liquid has been withdrawn the cap 12 is pulled outwardly to bring the valve into register with the aperture and seat the valve therein, thereby to stop the flow of liquid from the barrel.

After the contents of the barrel have been removed, or it is otherwise desired to seal the barrel, the latter is placed on end and the cap 12 is pushed inwardly toward the barrel. Substantial force is required to unseat the pouring spout from the bung hole and cause it to fall into the barrel. This force may be minimized by collapsing the body, as described hereinbefore, to reduce its outside diameter and thus draw it away from contact with the threaded bung hole. The pouring spout may be pushed into the barrel and to be housed wholly therein where it hangs suspended from the cap 12, which is secured in the bung hole.

If for any reason it is desired to remove the pouring spout from the barrel the body 1 is collapsed according to the procedure previously described. With the diameter of the body and shoulder 18 thus reduced sufficiently to pass through the bung hole, the pouring spout is readily withdrawn.

I claim:

1. A collapsible pouring spout for a barrel provided with a bunghole, said spout comprising a cylindrical body having resilient sidewalls, an open end capable of being folded radially inwardly to collapse said open end to sufficiently small compass to enable it to slide longitudinally through said bunghole, said walls being sufficiently resilient to return the body to its normal shape to seal said bunghole, said open end of said body being of larger diameter than the remainder of said body, said body also having a closed end, a partition extending transversely of said body defining a discharge chamber with said closed end, a portion of the body extending between said partition and said closed end being apertured to form a discharge spout thereby, said partition having a longitudinal passageway formed therein, tapered inwardly toward said discharge chamber, a conical valve adjustably arranged with respect to said aperture for controlling the flow of liquid therethrough, rod means connected to said valve for actuating said valve, means on the

terminal end of said rod means for pivotally connecting a bung hole cap thereto, and a shoulder means on the open end of said body for engaging the margins of said bung hole, tending to prevent leakage of liquid between said spout and said bung hole.

2. A collapsible pouring spout for a barrel provided with a bunghole, said spout comprising a cylindrical body having resilient sidewalls, an open end capable of being folded radially inwardly to collapse said open end to sufficiently small compass to enable it to slide longitudinally through said bunghole, said walls being sufficiently resilient to return the body to its normal shape to seal said bunghole, said open end of said body being of larger diameter than the remainder of said body, said body also having a closed end, a partition extending transversely of said body defining a discharge chamber with said closed end, a discharge spout communicating with said chamber, said partition having an aperture formed therein tapered inwardly toward said discharge chamber, a conical valve adjustably registering with said aperture for controlling the flow of liquid therethrough, rod means connected to said valve and extending through said closed end for actuating said valve, means on the terminal end of said rod means for pivotally connecting a bung hole cap thereto, and shoulder means on said enlarged end for engaging the margins of said bung hole tending to prevent leakage of liquid between said spout and said bung hole.

3. A collapsible pouring spout for the bunghole in a barrel, said spout including a resilient and collapsible cylindrical body having a hollow bore with one open end and one closed end, said body having resilient sidewalls, said open end being capable of being folded radially inwardly to collapse the same to sufficiently small compass to enable it to slide longitudinally through said barrel bunghole, said sidewalls being sufficiently resilient to return the body to its normal shape, the peripheral outline of said open end being larger than the peripheral outline of the remainder of said body whereby said remainder may pass through any aperture the same size as or larger than said open end peripheral outline, a discharge spout communicating with said bore through said closed end, said spout lying within the peripheral outline of said remainder, and valve means for controlling flow through said hollow bore, said valve means including an actuating rod operatively protruding through said closed end and carrying a closure cap having a peripheral outline larger than the peripheral outline of said remainder.

CORNELIUS W. MEYERS.
